Primary Examiner — Terry A Wallace

(74) *Attorney, Agent, or Firm* — Middleton Reutlinger

(57) **CLAIM**

The ornamental design for a cooler, as shown and described.

DESCRIPTION

FIG. 1 is a perspective view of a cooler design;
FIG. 2 is a front elevation view of the design of FIG. 1;
FIG. 3 is a rear elevation view of the design of FIG. 1;
FIG. 4 is a top plan view of the design of FIG. 1;
FIG. 5 is a bottom plan view of the design of FIG. 1;
FIG. 6 is a right side elevation view of the design of FIG. 1;
and,
FIG. 7 is a left side elevation view of the design of FIG. 1.
The broken line disclosure represents unclaimed portions of
the cooler in which the design is embodied.

1 Claim, 7 Drawing Sheets

US D888,503 S
